PROCESS FOR MAKING OZONIDES BY REACTING
OZONE WITH SUPEROXIDE

Mervin D. Marshall, Fombell, and Raymond F. Bratton,
Evans City, Pa., assignors to Callery Chemical Company,
Pittsburgh, Pa., a corporation of Pennsylvania
No Drawing. Filed Mar. 7, 1960, Ser. No. 13,383
14 Claims. (Cl. 23—184)

This invention relates to a new method for the production of ozonides. 10

Ozonides, as referred to throughout this specification, are compounds having the O_3^- anion. Such compounds have in the past at times been referred to as ozonates, but presently approved nomenclature names these compounds 15 as ozonides.

Heretofore, no good way to make ozonides has been known. Certain methods which were used have invariably resulted in very low yields and involve difficult recovery and purification techniques. These methods also were 20 specific in their nature and were not applicable to any wide variety of ozonides. Because of the relative instability of these compounds, these tedious processes have not been satisfactory because the products which are obtained tend to decompose during the processing steps required.

It is an object of this invention to provide a new method of making ozonides which is applicable to the production of several such compounds, including ozonides of alkali metals, alkaline earth metals and quaternary ammonium 30 cations.

Another object is to provide a method of making ozonides in which higher yields are obtained and less complicated procedures are required than in the prior known methods.

Still other objects will become apparent from time to time hereinafter.

The basis for this invention is our discovery that ozone will react with certain superoxides to produce the corresponding ozonide in yields much better than could be obtained by any other method. The process does not require special conditions and recovery is effected in a relatively simple and straightforward manner. Using potassium as an example, the reaction takes place in accordance with the following equation:

Any alkali metal superoxide can be used in the practice of our invention. The usefulness of lithium superoxide, however, is limited from a practical standpoint because it is unstable except at very low temperatures. Because the superoxides are most readily available and because of the desirability of the ozonides produced, the process is particularly valuable using potassium superoxide, KO_2 , and sodium superoxide, NaO_2 , although the other alkali metal superoxides, such as those of rubidium and cesium, can also be used if desired.

Any quaternary ammonium superoxide (R_4N) O_2 , where R is an alkyl or aryl group, can also be used in our method to produce the corresponding quaternary ammonium ozonide. Thus, among the quaternary ammonium superoxides which may be used are tetraalkylammonium superoxides, such as tetraethylammonium superoxide, tetrapropylammonium superoxide, tetrabutylammonium superoxide and tetraheptylammonium superoxide; mixed tetraalkylammonium superoxides, such as cetyl-trimethylammonium superoxide; and arylalkylammonium superoxides, such as trimethylphenylammonium superoxide. Tetramethylammonium superoxide is quite stable, and tetramethylammonium ozonate is both stable and is exceedingly rich in oxygen because of its low molecular weight. Thus, in practicing our method with

2

the quaternary ammonium superoxides, we prefer at present to use tetramethylammonium superoxide.

The quaternary ammonium superoxides are a relatively new class of compounds. They can be made by several methods, such as the metathetic reaction of the quaternary ammonium halide or hydroxide with potassium superoxide in liquid ammonia, or by electrolysis of the quaternary ammonium halide in liquid ammonia, using, for example, a magnesium anode and a platinum cathode and a temperature between $-65^\circ C.$ and $-80^\circ C.$, followed by reaction of the electrolysis products with molecular oxygen. Such compounds and processes for their preparation are also disclosed in the copending, co-assigned applications of Hashman and Renforth Serial No. 92,090, filed February 27, 1961, which is a continuation-in-part of abandoned application, Serial No. 832,864, filed August 10, 1959, and Hashman and Berkstresser Serial No. 97,388, filed March 21, 1961, which is a continuation-in-part of abandoned application Serial No. 832,863, filed August 10, 1959.

Alkaline earth metal ozonides are also made by our method from the corresponding alkaline earth metal superoxides. Thus, for example, calcium superoxide, CaO_2 , barium superoxide, BaO_2 , and strontium superoxide, SrO_2 , can each be used to produce the corresponding ozonide by the method described herein.

The temperature at which the reaction is carried out is not critical, but it should be considered in order to obtain the best yields. Ordinary ambient temperatures, i.e., about 20 to $30^\circ C.$, can be used, but because of the tendency of the ozonides to decompose at even moderately elevated temperatures it is preferred to use low temperatures. Temperatures as low as $-80^\circ C.$ and lower are feasible for use in carrying out the process, but the reaction at such low temperatures is quite slow. The preferred temperature is about $0^\circ C.$, where the reaction takes place at a satisfactory rate while little or no decomposition is ordinarily encountered. Higher temperatures than $30^\circ C.$ should be avoided, except in the case of the more stable ozonides, e.g., tetramethylammonium ozonide, in which case moderate heating can be used if desired. In all cases, the course of the reaction is marked by a pronounced color change; that is, as the ozonide is produced, the reaction mixture gradually becomes an intense red. If decomposition of the product is encountered, the color fades; thus with any particular reaction system the effect of the reaction conditions can easily be observed and modified if necessary.

It is not necessary to use pure ozone in carrying out our process. Rather dilute concentrations of ozone and oxygen, i.e., about 5% as produced in ordinary ozonizers, are satisfactory and are generally used. However, when higher concentrations are used the reaction rate is increased and more product is obtained in a shorter time.

Both the superoxides and ozonide products are decomposed by water so that moisture should be excluded from the reaction site and from the product obtained. Thus, the ozone-oxygen mixture should be free from moisture, and storage containers should be blanketed with a dry gas.

In one demonstration of the method of our invention, the process was carried out using 99% pure potassium superoxide, KO_2 . The powdered potassium superoxide was placed on a porous plate within a closed reactor and the reactor was cooled to about $0^\circ C.$ A dried gaseous mixture, 5% ozone in oxygen, was then passed through the superoxide for about three hours, the reactor was occasionally agitated in order to break up the superoxide and to expose fresh surfaces to the ozone. At the end of this time, the product mixture was extracted with liquid ammonia in order to separate the product from unreacted superoxide. After the liquid ammonia had been evapo-

rated about 480 milligrams of a dark red solid were obtained. Chemical and X-ray diffraction analyses were used to identify this product as potassium ozonide, KO_3 .

In other such examples, other ozonides, including, for example, sodium ozonide and tetramethylammonium ozonide, were prepared at various temperatures from $-112^\circ C$. to about $25^\circ C$. It was found that the best yields were obtained at about $0^\circ C$. or slightly above. Analysis and positive identification of the products was made through X-ray diffraction analysis. It was further demonstrated that the process is applicable to alkaline earth metal superoxides to produce alkaline earth metal ozonides, such as barium ozonide and calcium ozonide.

The ozonides which are made by the method of our invention have several uses. They may be used as oxidizing agents, where they exhibit powerful properties such that organic compounds can be oxidized to carbon dioxide, thereby providing an analytical method for determining the amount of carbon in such compounds. The ozonides can also be used as a source of oxygen, as, for example, in self-contained breathing apparatus or in confined spaces such as may be encountered in submarines. Oxygen is released from these compounds upon contact with moisture so that by passing exhaled air containing moisture through a container of ozonides in suitable apparatus fresh oxygen is produced. The equipment used may be similar to well-known apparatus used to produce breathing from superoxides.

According to the provisions of the patent statutes, we have explained the principle and mode of practicing our invention and have described what we now consider to be its best embodiments. However, we desire to have it understood that, within the scope of the appended claims, the invention may be practiced otherwise than as specifically described.

We claim:

1. A method of producing alkali metal ozonides, MO_3 where M is an alkali metal, which comprises reacting ozone with an alkali metal superoxide and recovering the alkali metal ozonide thus produced.
2. A method in accordance with claim 1 in which the reaction is carried out at a temperature of about $0^\circ C$.
3. A method in accordance with claim 1 in which the ozone is admixed with oxygen.
4. A method in accordance with claim 1 in which the alkali metal superoxide is sodium superoxide and the alkali metal ozonide produced is sodium ozonide.

5. A method in accordance with claim 1 in which the alkali metal superoxide is potassium superoxide and the alkali metal ozonide produced is potassium ozonide.

6. A method of producing quaternary ammonium ozonide of the formula R_4NO_3 , where R is alkyl, which comprises reacting ozone with a tetraalkylammonium superoxide and recovering the quaternary ammonium ozonide thus produced.

7. A method in accordance with claim 6 in which the reaction is carried out at a temperature about $0^\circ C$.

8. A method in accordance with claim 6 in which the ozone is admixed with oxygen.

9. A method in accordance with claim 6 in which the tetraalkylammonium superoxide is tetramethylammonium superoxide and the tetraalkylammonium ozonide produced is tetramethylammonium ozonide.

10. A method of producing alkaline earth metal ozonides, MO_6 where M is an alkaline earth metal, which comprises reacting ozone with alkaline earth metal superoxide and recovering the alkaline earth metal ozonide thus produced.

11. A method in accordance with claim 10 in which the reaction is carried out at a temperature about $0^\circ C$.

12. A method in accordance with claim 10 in which the ozone is admixed with oxygen.

13. A method in accordance with claim 10 in which the alkaline earth metal superoxide is barium superoxide and the alkaline earth metal ozonide produced is barium ozonide.

14. A method in accordance with claim 10 in which the alkaline earth metal superoxide is calcium superoxide and the alkaline earth metal ozonide produced is calcium ozonide.
